RACK STRUCTURE FOR FREIGHT VEHICLES
Harmon J. Bower, Roanoke, Va., and Daniel F. Freeman, Charlotte, N.C., assignors to Commercial Automotive Corporation, Winston-Salem, N.C., a corporation of North Carolina

Filed Mar. 20, 1961, Ser. No. 97,025
2 Claims. (Cl. 214—10.5)

The present invention relates to freight vehicles and more particularly to an improved rack structure therefor for lading spool-like objects such as full or empty beams of textile yarn, reels of wire or cables, or the like.

The spool-like objects which are contemplated to be carried by the improved rack structure of the present invention, are formed with end or head flanges and a barrel connecting the two flanges together. The yarn, wire or cable is normally wound on the barrel between the head flanges and, when the beam is full, is of a diameter only slightly less than the diameter of the head flanges. In transporting the full beams, it is extremely important that the peripheral edges of the head flanges avoid contacting the yarn, wire or cable on the other beams since the same would be damaged or soiled, or both, thereby. To insure that such contact does not occur, it is the usual practice to employ a set of tracks extending longitudinally of the vehicle and having flanges which engage the sides or faces of the head flanges to prevent lateral shifting thereof and to thereby maintain the head flanges in alignment. Two vertically aligned sets of tracks are usually employed so that superposed rows of beams may be transported in the same vehicle.

The problem of contact between the head flanges and the yarn, wire or cable naturally does not exist when empty beams are being transported. However, in the use of prior structures, the empty beams had to be transported in the same manner as full beams since the empty beams would be likely to shift during transit causing damage to the beams or to the vehicle or both. It can readily be appreciated that the number of empty beams which may be transported is materially restricted if only two superposed rows of beams may be transported with the head flanges in alignment since the head flanges are usually of relatively large diameter, i.e., 28, 32, or 36 inches. While the restriction as to the number of beams which may be transported is not a problem with full beams due to the heavy weight thereof relative to the weight capacity of the vehicle, it does constitute a problem with empty beams since the freight charge to the shipper for a load of empty beams is almost the same as with a load of full beams since the cost of operation of the vehicle is substantially the same for transporting empty beams as for transporting full beams and this cost must be passed on to the shipper.

It will therefore be apparent that the freight charge per pound is materially increased for the empty beams over the full beams since the empty beams weigh much less than the full beams and no greater number may be transported in the same vehicle. Since it is necessary for the shipper to have his empty beams returned to him for reuse, the high cost of transporting the empty beams back to the shipper materially increases the shipper's cost of producing the yarn or the like in which the beams are used.

It is therefore an object of the present invention to provide an improved apparatus for lading both full and empty beams for textile yarn or the like in freight vehicles which is capable of lading a large number of empty beams than has heretofore been possible whereby the cost per empty beam for transportation thereof is materially reduced.

A more specific object of the present invention is to

2

provide an improved apparatus for lading both full and empty beams for textile yarn or the like in freight vehicles of the character last described wherein means is provided whereby the head flanges of empty beams may be overlapped when the same are placed in the vehicle while still maintaining the beams against lateral shifting during transit such that a larger number of empty beams may be carried thereby reducing the shipping cost per beam.

A still more specific object of the present invention is to provide an improved apparatus for lading both full and empty beams for textile yarn or the like in freight vehicles of the character described wherein first or lower and second or upper pairs of vertically aligned tracks are provided in the freight vehicle for receiving said beams thereon, the upper pair of tracks being vertically adjustably mounted on the sides of the vehicle for accommodating various sized head flanges on the beams in the lower row, said upper tracks being movable to an out-of-the-way position adjacent the sides of the vehicle when not in use, and said upper and lower tracks being provided with means for allowing the head flanges of empty beams to be overlapped when the same are positioned thereon while maintaining the same against lateral movement during transit such that a larger number of empty beams may be transported thereby reducing the shipping cost per beam.

Some of the objects of the invention having been stated, other objects will appear when taken in connection with the accompanying drawings, in which—

FIGURE 1 is a side elevational view of the apparatus 30 of the present invention shown in a freight vehicle of the tractor-trailer type and showing full beams positioned thereon;

FIGURE 2 is a top plan view of the apparatus shown in FIGURE 1;

FIGURE 3 is an enlarged transverse vertical section taken substantially along line 3—3 of FIGURE 1;

FIGURE 4 is an enlarged, fragmentary sectional plan of the apparatus of the present invention showing empty spools positioned thereon;

FIGURE 5 is a sectional side elevation of the apparatus shown in FIGURE 4;

FIGURE 6 is a view similar to FIGURE 3 showing empty beams positioned thereon;

FIGURE 7 is an enlarged sectional detail of the upper track of the apparatus of the present invention showing the same in the out-of-the-way position adjacent the sides of the vehicle; and

FIGURE 8 is a side elevation of the structure shown in FIGURE 7.

Referring now to the drawings and more particularly FIGURE 1, the apparatus 10 of the present invention is preferably to be used with freight vehicles of the tractor-trailer type comprising a tractor 11 and a trailer 12 mounted on suitable wheels 13 for movement over a road or highway. Apparatus 10 is adapted to have spool-like objects or beams B positioned thereon in superposed rows in a manner to be later described. Beams B comprise a pair of spaced head flanges h connected by a barrel b and having a spindle s extending therethrough (FIGURE 6).

Beams B are adapted to be filled with strand material such as textile yarn, wire or cable by having the same wound upon the barrel b between the inside faces of the head flanges h to a diameter only slightly less than the diameter of head flanges h when the beams B are full (FIGURE 3). Beams B may be of conventional size which usually is measured by the diameter of the head flanges h with the usual sizes being 28, 32, and 36 inches in diameter.

Apparatus 10 generally comprises a first pair of tracks 14, 15 (FIGURES 2 and 3) mounted on the floor 16 of trailer 12 and spaced a sufficient distance apart to corre-

spond to the length of barrels b on beams B such that the head flanges h will be received thereon when beams B are placed in the trailer 12. Tracks 14, 15 extend longitudinally of the floor 16 of trailer 12 for substantially the full length thereof such that beams may be positioned throughout substantially the full length of trailer 12 (FIGURE 2). Tracks 14, 15 have outside flanges 20, 21 thereon, respectively, which are on the side of the tracks adjacent sides 22 of trailer 12 and which serve to maintain the head flanges h of beams B therebetween to prevent lateral movement of the beams during transit. It is noted that flanges 20, 21 are spaced a greater distance apart than the distance between the outside faces of head flanges h for reasons to be presently described. It is also noted that the width of each of the tracks 14, 15 is greater than twice the thickness of head flanges h for reasons also to be presently described.

Track 14 has a second flange 23 thereon which extends for substantially the full length thereof and is positioned a distance from outside flange 20 at least equal to the thickness of one of the head flanges h of beams B. The spacing of flange 23 from flange 20 allows head flanges h of alternate empty beams B to be positioned between flanges 20 and 23. Flange 23 is spaced from the inner side of track 14 a distance at least equal to the thickness of one of the head flanges h of the beams B such that the head flanges h of the remaining or intervening empty beams of said row may be positioned between flange 23 and the inner side of track 14. Track 15 is of a width at least equal to twice the thickness of one of the head flanges h of the beams B and the width of flange 23. Flange 23 is spaced a sufficient distance from outside flange 21 on track 15 for receipt of a beam B therebetween with flanges 21 and 23 engaging the outside faces of the head flanges h to prevent lateral shifting during transit.

It can therefore be seen that the head flanges h on one side of empty alternate beams B in said row may be positioned between flanges 20 and 23 and the head flanges h on the same side of the remaining empty beams B may be positioned between the flange 23 and the inner side of track 14 such that the head flanges h of successive empty beams B are out of alignment with each other and are overlapped such that the barrels b of the empty beams B will be closer together allowing a larger number of empty beams to be placed on the tracks 14, 15 than would be possible if the head flanges were in alignment.

Suitable braces 24, 25 are positioned between the outer sides of flanges 20, 21 and the sides 22 of trailer 12 to brace tracks 14, 15 against lateral movement during transit.

A set of upper tracks 30, 31 are provided in vertical alignment with lower tracks 14, 15 and are substantially identical therewith having outside flanges 32, 33 thereon which correspond to outside flanges 20, 21 on tracks 14, 15. Track 30 which is positioned over track 14 has a flange 34 thereon which corresponds and is identical with flange 23 on track 14. Tracks 30, 31 have additional members 35, 36 connected thereto to strengthen the tracks for better support of the upper row of beams.

Tracks 30, 31 are fixed to the inner ends of suitable arms 40, 41 which are mounted at their outer ends on suitable brackets 42, 43 by suitable pivot pins or bolts 44, 45. Brackets 42, 43 are fixed to the sides 22 of trailer 12 by any suitable means such as welding or the like, not shown, and have vertically extending slots 46, 47 formed therein, respectively, for vertical adjustment of the tracks 30, 31 relative to the floor 16 of trailer 12 to accommodate various head flange sizes on beams B in the lower row of beams.

Tracks 30, 31 and arms 40, 41 are movable about pivots 44, 45 to an out-of-the-way position, shown in FIGURE 7, adjacent the sides 22 of trailer 12 when not in use. Tracks 30, 31 and arms 40, 41 are releasably secured in the out-of-the-way position by means of brackets 50

5 mounted on sides 22 and releasably having suitable openings therein which mate with suitable openings in the flanges 32, 33 of tracks 30, 31. Locking pins 51 are provided for insertion into the mating opening in flanges 32, 33 and brackets 50 for releasably locking the tracks and brackets together. Pins 51 are secured to the sides 22 of trailer 12 by means of chains 52 which are connected to the sides by suitable eyelets 53.

10 Suitable anchoring or tiedown means 60 are provided for connection between spindles 5 on beams B and tiedown points mounted on the floor 16 of trailer 12 for securing the beams against longitudinal movement along the tracks 14, 15, 30 and 31 during transit. The tiedown means 60 are shown in the form of suitable chains 15 or cables which have suitable tightening means 61 positioned intermediate the ends thereof. Also, suitable scotches 62 are provided at opposite ends of the rows of beams for aiding in holding the same against longitudinal movement along the tracks. It is noted that the forward scotches 62 have suitable tiedown means 60 connected thereto for withstanding the forward movement of the rows of beams during braking of the tractor 11 and trailer 12. Tiedown means 60 may be of any conventional form or may take any desired arrangement since the same does not form any part of the present invention and is shown for illustrative purposes only.

20 In operation, when it is desired to transport full beams in the vehicle embodying the improved apparatus of the present invention, the first row of full beams are 25 placed on tracks 14, 15 between flange 23 on track 14 and flange 21 on track 15 with the head flanges in horizontal alignment. It is noted that track 15 is positioned a sufficient distance from the corresponding side 22 of trailer 12 such that the flange 21 thereon is spaced the same distance from the corresponding side 22 as flange 23 on track 14 such that the center of gravity of the full beams will be in vertical alignment with the longitudinal center line of the trailer 12. This spacing of tracks 14, 15 insures that the weight of the full beams is evenly distributed on the wheels 13 of the tractor 11 and trailer 12. As the full beams B are placed on tracks 14, 15, the tiedown means 60 is applied to selected beams to hold the lower row of beams against movement.

25 When tracks 14 and 15 have received their full complement of full beams B, tracks 30, 31 are released from their out-of-the-way position by removal of pins 51 from the mating openings in flanges 32, 33 and brackets 50. When released, tracks 30, 31 are lowered about their pivot points 44, 45 into engagement with the periphery of the head flanges h of the lower row of beams B.

30 With the upper tracks 30, 31 in position on the head flanges on the lower row of beams, full beams B are placed on the upper tracks between flange 33 on track 31 and flange 34 on track 30 with the head flanges thereof in horizontal alignment with the other beams in the upper row and in vertical alignment with the head flanges of the beams in the lower row such that the head flanges of the beams in the lower row will serve as supports for the upper row of beams. As the beams are positioned on the upper row, the tiedown means 60 are connected 35 to selected beams in any desired manner such that the same are prevented from moving during transit. It is noted that the forwardmost beam at each row has tiedown means 60 connected thereto and also engages the forward scotches 62 to prevent forward rolling movement off the forward end of the tracks 14, 15, 30, 31 with consequent damage to the forward wall of the trailer 12 and to the beam. When the full complement of full beams has been placed on the upper tracks 30, 31, the rearmost scotch 62 is placed thereon and tiedown means 60 is secured thereto to prevent rolling movement of the beams off the rearward end of tracks 30, 31. The beams are then transported to their destination in the trailer 12 at which time they are unloaded in reverse 40 order of steps to the loading.

When it is desired to haul empty beams B, the empty beams are placed on the tracks 14, 15 in alteration with one of the head flanges of every other beam between flanges 20, 23 on track 14 and with one of the head flanges of the alternate beams on the opposite side of flange 23 from flange 20 between flange 23 and the inner side of track 14. This alternate positioning of the head flanges on opposite sides of flange 23 allows the head flanges to overlap so that a larger number of empty beams may be placed in a row on tracks 14, 15. The same procedure is followed in placing empty beams on the upper tracks 30 and 31 with the same result. Tiedown means 60 are employed to hold empty beams against movement during transit in substantially the same manner as for full beams.

Since the head flanges *h* of the lower row of beams B support the upper tracks 30 and 31, the head flanges of the lower row of beams should preferably all be of the same diameter so that the tracks 30, 31 are evenly supported at the same level throughout their length. No such restriction as to the head flange size of the upper row exists since the same do not serve a supporting function.

It will therefore be apparent that an improved rack structure for freight vehicles has been provided wherein the same may carry full beams of textile yarn or the like with the weight evenly distributed on either side of the longitudinal center line of the trailer or freight vehicle and with the beams secured against lateral and longitudinal movement during transit. Further, when empty beams are to be transported, the improved rack structure receives the same with the head flanges thereof in overlapping relation such that a substantially larger number of empty beams may be transported than would be possible if such head flanges were in alignment, the overlapping head flanges of the empty beams being also maintained against both lateral and longitudinal movement during transit. Therefore, it will be still further apparent that the improved rack structure of the present invention materially reduces the shipping cost per beam of empty beams while providing all of the advantages for shipping full beams without increasing the cost of installation or maintenance.

In the drawings and specification there has been set forth a preferred embodiment of the invention and, although specific terms are employed, they are used in a generic and descriptive sense only and not for purposes of limitation, the scope of the invention being defined in the claims.

We claim:

1. In a wheeled vehicle having a body provided with an elongate floor and side walls, the combination of means carried by and extending longitudinally of the body for receiving superposed rows of parallel spool-like beams each having spaced apart head flanges connected

by a barrel adapted to have textile material or the like wound thereon, said means comprising a first pair of spaced apart, elongate, parallel track members mounted on said floor on opposite sides of the longitudinal center line of said body, and a second pair of spaced apart, elongate, parallel track members pivotally mounted on the sides of said body for movement between an out-of-the-way position adjacent the sides of said body and an operative position in vertical alignment with said first track members and in spaced relation thereto, the distal sides of the track members of each of said first and second pairs adjacent the sides of said body having upstanding side flanges, one track member of each of said first and second pairs on the same side of the longitudinal center line of said body having an upstanding flange in a medial portion thereof and extending longitudinally thereof parallel to said side flange thereon and spaced from said side flange thereon a sufficient distance to permit the receipt of a head flange of a spool-like beam therebetween, said medial flanges on said one track members being spaced from the longitudinal center line of said body substantially the same distance as the side flanges on the other track members of said first and second pairs, said medial flanges on said one track members and said side flanges on said other track members of each of said first and second pairs being adapted to selectively receive therebetween a row of full spool-like beams having textile material or the like thereon with the center of gravity of the full beams in vertical alignment with the longitudinal center line of said body and alternate beams of a row of staggered empty spool-like beams having alternate and intervening beams therein with the head flanges thereof overlapped, said medial flanges and said side flanges on said one track members of each of said first and second pairs being adapted to receive therebetween one of the head flanges of the intervening beams in the row of staggered empty beams.

2. The structure set forth in claim 1 including means for releasably securing said second track members in the out-of-the-way position, and means for vertically adjusting the pivot points of said second track members to accommodate spool-like beams with head flanges of varying size.
